ANCHOR ESCAPEMENT FOR TIMEPIECES

Marc Huguenin, Geneva, Switzerland, assignor
to Montres Rolex S. A., Geneva, Switzerland,
a firm of Switzerland

Application June 14, 1952, Serial No. 293,502

Claims priority, application Switzerland
August 13, 1951

2 Claims. (Cl. 58—121)

1

The present invention has for its object an anchor escapement for time-pieces. This escapement is characterized by the fact that the edges of each anchor pallet or arch-piece project with reference to the upper and lower surfaces of the anchor so as to provide between the projecting parts of the pallet walls and said upper and lower surfaces of the anchor longitudinal and transversal dihedral angles forming capillary passages for a provision of oil. The longitudinal passages along one surface of the anchor are furthermore connected with the longitudinal passages along the second surface by further passages constituted by the dihedral angles formed on one hand between the transverse surface of the anchor and the abutment surface of the pallet and, on the other hand, between said transverse surface of the anchor and the impact surface of the pallet, this latter dihedral angle being equal at a maximum to 90°.

Accompanying drawings illustrate by way of example a preferred embodiment of the object of my invention. In said drawings:

Fig. 1 is a perspective view of a section of an anchor escapement.

Fig. 2 illustrates diagrammatically the passages provided for the lubricating oil.

The anchor illustrated is designated by 1 and the escape wheel by 2. The pallets or arch-pieces of the anchor shown at 3 have their longitudinal ridges 4, 5, 6 and 7 projecting with reference to the upper and lower surfaces 8 and 9 of the anchor. Dihedral angles are thus formed between the said surfaces 8, 9 of the anchor and the projecting portions of the pallet walls. These dihedral angles form capillary passages 10, 11, 12 and 13, 14, 15 for a provision of oil as illustrated diagrammatically in Fig. 2.

The passages 12 and 13 on the opposite surfaces of the anchor are interconnected by a passage 16 formed by the dihedral angle defined by the abutment surface 17 of the corresponding pallet and the transverse surface 18 of the anchor. Similarly a passage 19 connects the passages 10 and 15, said passage 19 being constituted by the dihedral angle defined by the transverse surface of anchor and the impact surface of the pallet. It should be remarked that bevelled surfaces such as 20 are provided in the transverse surface of the anchor so that the dihedral angles forming the passages 19 may be acute and thereby the oil may be prevented from spreading over the transverse surface of the anchor.

2

The different above-mentioned passages form thus a closed circuit illustrated in dot and dash lines in Fig. 2 and through which the provision of oil is adapted to flow. The abutment surface 17 of each pallet is comparatively short so that the teeth 2a of the escapement wheel may enter the meniscus formed by the oil inside the passage 16 at each abutment stage. The tooth is then laden with oil that lubricates the impulse surface 21 of the pallet. It may occur that a certain amount of oil left by the tooth 2a at the moment at which it leaves the pallet, collects on the impact surface. This oil moves gradually towards the bevel 20 and it then engages the latter and collects with the oil in the passage 18. This oil removed by the teeth 2a of the escape wheel follows thus the path 22 shown as an interrupted line in Fig. 2.

What I claim is:

20. 1. In a time-piece, the provision of an anchor escapement comprising an anchor having two parallel outer surfaces and a transverse surface and provided with pallet recesses opening into said transverse surface, a pallet fitted in each of said recesses and provided with outer surfaces that project beyond the corresponding outer surfaces of the anchor, said pallet including a terminal operative section projecting beyond the transverse surface of the anchor, said pallet defining between its lateral and terminal surfaces engaging the recess surfaces and each outer surface of the anchor, dihedral angles at the utmost equal to 90° forming interconnected capillary paths adapted to receive a provision of oil, the terminal section of the pallet forming with the transverse surface of the anchor further dihedral angles defining capillary paths connecting the first mentioned paths corresponding to the two outer surfaces of the anchor, and a toothed escape wheel cooperating with the anchor pallets.
2. In a timepiece, including an anchor escapement, comprising an anchor having two parallel outer surfaces and a transverse surface and provided with pallet recesses opening into said transverse surface, two pallets fitted in said recesses, and a toothed escape wheel cooperating with said pallets, each pallet being provided with outer surfaces that project beyond the corresponding outer surfaces of the anchor, and including a terminal operative section projecting beyond the transverse surface of the anchor, each pallet defining, between its lateral and terminal surfaces engaging the recess surfaces and each outer sur-

face of the anchor, dihedral angles, and the terminal section of the pallet forming with the transverse surface of the anchor further dihedral angles; the feature that said dihedral angles are at the utmost equal to 90°, that they define interconnecting capillary paths, and that oil is provided in said paths, whereby the teeth of said escape wheel enter the oil meniscus in one of said paths, take drops of said oil with them, and leave at least a part of said oil in another of said paths, the whole in such a way that, as said paths

are interconnected, said oil left by the teeth of the escape wheel can return back to the place where it has been taken away.
